UNITED STATES PATENT OFFICE.

MARY McCALL LIVINGSTON, OF THOMASVILLE, GEORGIA.

GARMENT-SUPPORTING APPARATUS.

SPECIFICATION forming part of Letters Patent No. 730,137, dated June 2, 1903.

Application filed February 3, 1903. Serial No. 141,717. (No model.)

To all whom it may concern:

Be it known that I, MARY McCALL LIVINGSTON, a citizen of the United States, residing at Thomasville, in the county of Thomas and State of Georgia, have invented certain new and useful Improvements in Garment-Supporting Apparatus; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in garment-supporters, and especially to a simple and efficient means for holding up diapers; and it consists in the provision of a button-tab attached to one end of a suspender and adapted for attachment to the shank portion of a safety-pin caught in the front part of the diaper, while the portion of diaper at the back of the child is adapted to be engaged by a safety-pin, which is secured to an elastic strap having a button-hole-tab for connection with a button carried by the suspender.

The invention consists further in the novel construction, combination, and adaptation of parts, as will be hereinafter fully described, and then specifically defined in the appended claim.

The invention is clearly illustrated in the accompanying drawings, which, with the letters of reference marked thereon, form a part of this invention, and in which similar letters of reference indicate like parts, in which—

Figure 1 is a perspective rear view of my garment-supporting apparatus shown as applied to a diaper. Fig. 2 is a detail view showing the manner of attaching a portion of the suspender to a portion of a diaper. Fig. 3 is a detail view showing the manner of supporting the portion of the diaper at the front of the body of a child. Fig. 4 is a central sectional view through Fig. 3.

Reference now being had to the details of the drawings by letter, A designates a tab,

which is adapted to be secured to an end B of the suspender E, and D designates a button, which is fastened to the end B, said button D being adapted to engage the buttonhole F, which is formed in the tab A, as shown in Fig. 3, and form a supporting means for a safety-pin H, while the point of the pin is adapted to be caught into the diaper K, as shown. The tab described and the pin carried thereby are intended to support the portion of the diaper which is held at the front of the child, and the portion which is supported at the back of the infant comprises the elastic strap N, which is permanently fastened to the safety-pin M, which latter is designed to be caught in the diaper, as shown in Fig. 2, and the other end of said strap is provided with a buttonhole N', which is adapted to be buttoned to a button O, which is fastened to an end Q of the suspender. Another end R of the suspender is provided with a buttonhole R', which after the elastic strap N has been fastened over the button O is designed to be buttoned over the same button O, thus retaining the strap N upon the button O and between the two ends Q and R.

By the provision of a garment-supporting apparatus, as hereinbefore described, infants' diapers may be satisfactorily held up without being continually torn, as is the case with the common way of supporting diapers, where the pins are used for engagement with both the diaper and the suspender direct. By the provision of my improved supporting apparatus the diaper may be easily attached and detached, the elastic strap will allow of various movements of the body, giving under a strain, and as the safety-pin is not permanently secured to the suspender the latter may be easily washed.

Having thus described my invention, what I claim to be new, and desire to secure by Letters Patent, is—

A diaper-supporting apparatus, comprising, in combination with a suitable suspender, a buttonhole-tab fastened to one end B of the suspender, a button engaged by said tab to support a safety-pin, an elastic strap, a but-

tonhole therein, a safety-pin secured to said strap, a button O fastened to an end Q of the suspender, an end R with buttonhole therein, said strap adapted to be held upon said but-
5 tonhole and between the ends Q and R, the latter being adapted to be held upon said but-
ton, as shown and described.

In testimony whereof I hereunto affix my signature in presence of two witnesses.

MARY McCALL LIVINGSTON.
